MACHINE FOR CLEANING THE MATRICES
OF TYPESETTING MACHINES

Ernst Albrecht, Berlin, Germany

Application June 20, 1934, Serial No. 731,445
In Germany June 27, 1933

5 Claims. (Cl. 15—77)

This invention relates to a machine for cleaning the matrices of type setting machines and of the kind wherein the matrices are made to travel past rotary brushes which effect the cleaning by means of a suitable cleaning fluid, for instance benzine or the like.

The object of the invention is to obtain a machine of this kind which is of simple construction, easy to supervise, and reliable in its operation, and the invention consists essentially in the provision of a pair of parallel feed screws to which the matrices are delivered one by one from a pile and from which they are led between endless travelling drying bands to an assembler, rotary brushes being provided some of which act on the pile for cleaning the edges of the matrices, while others operate over a guideway between the feed screws for cleaning the faces thereof, and means being provided for reversing the matrices on the guideway so as to present first one and then the other face to the brushes.

Fig. 1 of the accompanying drawings represents a side view of a machine constructed according to the invention,

Fig. 2 is an end view of the same,

Fig. 3 is a plan view of the machine,

Fig. 4 represents an edge view and a plan view of one of the matrices.

Fig. 5 is a fragmentary, sectional side view of the machine on an enlarged scale,

Fig. 6 is a corresponding plan view,

Fig. 7 is an enlarged side view of the drying and assembling mechanism,

Fig. 8 is a fragmentary, sectional view of the device for ejecting the matrices from the pile, and

Fig. 9 is a section on the line IX—IX of Fig. 8.

The device comprises a table top 2 which is supported by legs 1 and which carries in suitable bearings two parallel, horizontal feed screws 31 and 32 adapted to receive the matrices between them and to move said matrices along a guideway 39 by the engagement of the screw threads with the ears of the matrices. Each screw is provided with two threads 35 and 36 one of which is narrower than the other, and the threads are cut and pitched so that wide spaces are provided for the reception of the long ears 37 of the matrices, and narrow spaces for the reception of the short ears 38 thereof. One screw has right hand and the other left hand screw thread, and the screws are rotated by intermeshing gears 33 in opposite directions and towards the matrices so as to urge the latter against the guideway.

Rotary brushes 47 and 48, driven by means of

belt pulleys 49 and 50, are arranged over the guideway 39 for cleaning the faces of the matrices, means being provided for reversing the matrices on the guideway so that first one and then the other face of each matrix will be exposed to the brushes. This reversal is effected through the medium of a forked arm 44 which is pivotally supported at 42 between supporting brackets 43 some distance above the guideway and which bears with its free, forked and hooked end against the guideway. The latter is formed with slots 40 in which the hooks 41 of the arm normally engage. On the hooks being engaged by the leading end members of a travelling matrix, the arm 44 will be turned about its pivots 42, as shown by dotted lines in Fig. 5, the matrix being at the same time turned over in the vertical, longitudinal plane of the guideway and deposited on the latter with the opposite face in position to be cleaned by the next brush. In order to facilitate the reversal of the matrices, the space between the screw threads is widened for about $\frac{3}{4}$ of the circumference of the screw at the point where the reversal takes place.

The matrices are delivered on to the guideway 39 from a pile located in a magazine 6. The latter has a vertical guide member 7 which is ribbed in conformity with the notches in the recessed ends of the matrices. The pile is supported at the bottom of the magazine by spaced ledges 10 and 11 on which the lowermost matrix rests by means of its ears, as shown in Fig. 9, and off which it is slid on to the guideway 39. This is effected by means of a reciprocating slide 14 and a pawl 12 which latter is pivoted at 13 to the slide 14 and supported by a spring 15 in position to engage and eject the lowermost matrix from the pile on the slide being reciprocated. A plate 8 arranged in a central position in the magazine and in a vertical plane, serves as a detent for the matrix next above the one to be ejected. The free end of the plate is reduced as shown at 8a and adapted to engage in the groove 9 in the ejected matrix for guiding the latter until it is slid off the ledges. The pawl 12 is provided with laterally projecting studs 16 adapted to engage the bevelled ends of bevelled guide rails 17, formed by the lower edges of the walls of the magazine 6, for depressing the pawl and preventing the latter from coming into contact with any but the lowermost matrix of the pile. There is also a guide member 29 which is pivoted at 28 to the back of the magazine and arranged so as to be deflected by the ejected matrices in opposition to a spring 30. In its turn the guide member de-

presses the matrix and ensures a correct positioning thereof between the feed screws.

The slide 14 is reciprocated by means of an arm 19 which is rocked about a centre 18 through the medium of a rod 20 which bears under the pressure of a spring 20' against a cam 21. The latter is driven by gears 34 from one of the feed screws, so that the movement of the latter will be synchronized with the matrix ejecting slide 14.

10 The magazine 6 is open so that the edges of the matrices can be cleaned while the matrices pass through the magazine. This cleaning is effected by means of brushes 22 arranged one at each side of the magazine. The brushes are carried by slides 23 in a support 24 and are adjustable by means of screw spindles 25. A similar arrangement is employed, as shown in Fig. 1, for adjusting the brushes 47 and 48 relative to the guideway 39. The brushes 22 are rotated through the medium of conical gears 26 and a belt pulley 27.

The cleaning brushes are fed with benzine, for instance by hand, and a subsequent wiping and drying of the matrices is therefore required. This wiping and drying process is effected through the medium of a pair of co-operating, endless, travelling bands 55 and 56, one guided on rollers 51 and 52 and the other, on rollers 53 and 54, all arranged under the table top 2. The feed screws 30 deliver the matrices into a chute 45 whence they are led through a channel 46 into position for being received between the drying bands. The lower band moves over a rigid supporting surface 57, and the upper band is pressed against the lower band by a plate 58 which is suspended from links 59 and preferably controlled by a spring 60, so that the matrices will be clamped between the bands. The latter are moved at different speeds, so that a rubbing and wiping action will take place whereby the matrices will be delivered from the bands in dry and perfectly clean condition. An electric heating element 61 may be employed for heating either the plate 58 or the supporting surface 57. A tensioning roller 62 may be provided for the lower band 56, and a press roller 51a may be arranged to bear against the upper roller 51 in order to ensure a uniform movement.

The drying bands deliver the cleaned matrices through a chute 63 into a container 66 wherein they are assembled. The container is provided with a plurality of compartments 65 all of which can, by a shifting of the container, be brought into receiving position. In the arrangement shown, the container is supported by means of rollers on inclined rails 72 and has a tendency to move down the track thus produced. A catch lever 69, which is controlled by a spring 70, is

adapted to engage in a rack 71 in the container for arresting the latter with any one of the compartments in receiving position. The matrices are packed endwise in the container by means of a star wheel 64, each compartment having a slideable partition 67 which recedes in proportion as the packing progresses. As the partition reaches the end of the compartment, it strikes against and rocks the lever 69, first to release the container which therefore shifts into the next position 10 wherein it is re-arrested by the catch. The action is repeated for each compartment. The partition of the last compartment may be adapted to operate an electric switch for stopping the machine when the compartment is full.

I claim:

1. A machine for cleaning the matrices of type setting machines comprising an elongated guideway, means for feeding the matrices in a single file along said guideway, means arranged midway of the ends of the guideway for reversing the matrices on the latter in the vertical longitudinal plane thereof, and brushes arranged above the guideway for cleaning the faces of the matrices before and after the reversal thereof.

2. A machine for cleaning the matrices of type setting machines, comprising an elongated guideway, means for feeding the matrices one by one on to said guideway, a pair of feed screws having threads pitched in conformity with the matrix ears, said screws being arranged at opposite sides of the guideway and operative to engage the matrices and feed them forwards, means arranged midway of the end of the guideway for reversing the matrices on the latter in the vertical longitudinal plane thereof, and brushes arranged above the guideway for cleaning the faces of the matrices before and after the reversal thereof.

3. A machine as claimed in claim 2 wherein the matrix reversing means comprises an arm 40 pivotally suspended above the guideway and adapted to turn in the vertical longitudinal plane of the latter, and a hook at the free end of the arm normally maintained in the path of the matrices and operative to engage the leading 45 ends thereof and turn the matrices in the plane of movement of the arm.

4. A machine as claimed in claim 2 wherein the matrices are reversed by movement about one pair of ears and wherein the space between the 50 threads of the feed screws is widened at the reversing point for facilitating the reversal.

5. A machine as claimed in claim 2 wherein the feed screws are operative to urge the matrices against the guideway.

ERNST ALBRECHT.
